UNITED STATES PATENT OFFICE.

JEAN ALBERT AUGUSTE D'AYGUESVIVES, OF PARIS, FRANCE.

COPYING-PRESS.

No. 829,246.

Specification of Letters Patent.

Patented Aug. 21, 1906.

Application filed September 15, 1905. Serial No. 278,663.

To all whom it may concern:

Be it known that I, JEAN ALBERT AUGUSTE D'AYGUESVIVES, gentleman, residing at 132 Avenue Victor Hugo, Paris, France, 5 have invented Improvements in Presses, of which the following is a full, clear, and exact description.

This invention relates to an improved press with compensating plate especially 10 adapted to be used as a copying-press.

This press is so constructed as to require the smallest possible space, giving at the same time a pressure which will be powerful and uniform at all points. It is not necessarily 15 secured to a support and insures a uniform pressure with the same stroke of the operating-lever whatever be the thickness of the copy-book or of the parts to be pressed.

The accompanying drawings show by way 20 of example a copying-press made according to this invention.

Figure 1 is an elevation. Fig. 2 is a plan view, the cover being removed. Fig. 3 is a vertical section made on the line A A of Fig. 25 2. Fig. 4 is a detail view showing the movable plate seen from underneath. Fig. 5 is a partial section made on the line B B of Fig. 3.

As shown in the drawings, this press comprises, first, a stationary frame having a base 30 a and an upper cover connected with the former by uprights c, forming ties; second, a compensating plate d, movable between the base a and the cover b, this plate being guided in its vertical motion by means of the uprights c; third, a driving-shaft e, located in the base a, carrying eccentrics f, on which rests the movable plate d and ending in a square adapted to receive an operating-lever g.

In order to allow the pressure to be regulated 40 independently of the stroke of the operating-lever, this press possesses the following adjusting device: The plate d is carried by eccentrics f through a movable part h, carrying two wedges i, located in recesses of corresponding shape, Fig. 3, provided in the plate d. An operating - screw j, rotating within a nut k, embedded within the plate d, allows a shifting of the wedges in their recesses, which in virtue of their inclined surfaces 45 50 55 will impart a shifting motion to the wedges i, and therefore to the part h. By operating the screw j the position of the part h can be regulated at will, so that the latter will be flush with the lower face of the plate d or will project more or less. The wedges i will be preferably secured to the plate d through

screws l, arranged at the bottom of the recesses, Figs. 3 and 5, and the heads of which are inserted in dovetailed guides with which each wedge is provided.

60

In order to prevent the driving-shaft from returning backward under the action of exerted pressure, a half ring or collar m is secured to the base a, so as to exert upon the shaft e a friction which can be adjusted according to the amount of pressure.

65

The copy-book being placed on the plate d, it will be only necessary to move the lever g to impart an angular displacement to the shaft e, and therefore to the eccentrics f. The latter will lift the plate d, that presses the copy-book with great force against the upper cover b. By returning the lever g the eccentrics f no longer press upon the plate d, which latter is again brought down under the action 70 of its weight, and thereby allows the removal of the copy-book. Therefore the operation is very simple and very quick.

75

The adjusting appliance h i j enables an arrangement such that the maximum pressure will always be exerted at the moment when the point of contact between the eccentrics and the part h lies on vertical lines passing through the axis of the shaft e, so that the said eccentrics will not tend to return backward on account of the reaction.

80

In the present system of press the strain being communicated at different points to the plate d the pressure exerted by the latter is approximately uniform at every point.

90

For presses of small size—as copying-presses, for example—two eccentrics like those represented in the drawings will be sufficient. For presses of larger size the shaft e can carry a greater number of eccentrics, and in the case of powerful presses of very large sizes I employ a greater number of shafts arranged parallelly and connected together by any transmitting-gear, either by a chain or by links and cranks, &c. Furthermore, the presses of large sizes can be provided side-wise with hooks, enabling a firm connection to be made between the upper cover and the base at several points, and therefore to prevent any bending of the former.

105

In this press only vertical strains will be exerted, the action and reaction of which will be respectively supported by the base a and the cover b. Under these conditions it is not necessary to secure the press to a support.

110

The present device has the further advan-

tage of occupying very little space and leaves the upper face of the cover entirely free, which face can be utilized as a table.

With this construction of press the copy-book can be preserved against indiscretions by locking the same against the upper cover *b*, by lifting the plate *d*, and by removing the operating-lever *g*.

I claim—

- 10 In a press, in combination, a base-plate, a shaft rotatably mounted therein and carrying eccentrics, a movable plate having recesses in the side thereof adjacent to said ec-

centrics, a pair of movable wedges rigidly connected together mounted in said recesses 15 and resting on said eccentrics, a cover-plate toward which said movable plate may advance, and means for adjusting said wedges.

The foregoing specification of my improvements in presses signed by me this 17th day 20 of August, 1905.

JEAN ALBERT AUGUSTE D'AYGUESVIVES.
